UNITED STATES PATENT OFFICE

CECIL R. CRARY, OF DETROIT, MICHIGAN, ASSIGNEE TO GRACE T. CRARY, OF DETROIT, MICHIGAN

CLOSURE

Application filed April 26, 1926. Serial No. 104,759.

This invention relates to closures, and particularly relates to hinged closures.

One object of the invention is to utilize parts which hingedly attach a closure to a support to effect a firm and sealed seating of the closure in its closed position, upon said support.

Another object is to adapt a hinged closure to be rotated upon its support to a limited extent, and to effect a sealing engagement of the closure with the support through such rotation.

Still another object is to provide a novel quick detachable hinge connection between a closure and its support.

A further object is to provide an improved closure for the filler tube of a radiator, and to adapt said closure to replace the filler tube caps of standard radiators.

These and various other objects the invention attains by the construction hereinafter described, and illustrated in the accompanying drawings, wherein:

Figure 1 is a diametrical vertical section of still another alternative construction.

Figure 2 is a similar view, showing the cap member in closed position.

Figure 3 is a horizontal sectional view taken on the line 3—3 of Figure 2.

Figure 4 is a plan view of the same with the cap member in open position.

Figure 5 is a view of the same in side elevation.

Figure 6 is a fragmentary section on line 6—6 of Figure 3.

In Figures 1 to 6 inclusive the hinge is fully concealed in the closed position of the closure. In this construction an adapter ring 39 is screwed into the collar 40 of the filler tube 41. From the flange 42 of said adapter ring a pair of diametrically opposed lugs 43 and 44, project outwardly, the lug 44 having a T-shape. Said lug forms a hinge member to mount the flanged cap 45. In the flange of said cap, adjacent to the top thereof a pair of diametrically opposite grooves 46 and 47 are interiorly formed, to receive the lugs 43 and 44, said grooves being slightly inclined so as to cause said lugs to exert a downward pressure at opposite points of the cap responsive

to a suitable rotation of the cap. From the lower end of the groove 47 extends a guide way for the T-head of the lug 44, which guide way provides pockets 48 engaged by the head opening from said groove toward the lower edge of the cap member, said pockets being one at each side of a groove 49 in which the stem of said lug may travel. 50 designates an entrance way for the lug 43 extending from the lower end of the groove 46 to the lower end of the flange of the cap. A gasket ring 51 inserted in the upper portion of the cap member is adapted to be compressed against the flange 42 as in the first-described construction.

It will be noted that provision is made for hingedly mounting the closure and to subject said closure, when rotated, to a pressure whereby it is firmly seated in sealing engagement with a suitable support.

It is to be understood that the uses of the invention have been merely exemplified by this disclosure, and that the invention is capable of many uses not requiring enumeration herein.

What I claim is:

1. The combination with a container having an opening, of a ring projecting from said container surrounding said opening, a closure for said opening rotatable in its closed position around said opening to a limited extent, and having an annular flange, and means carried by said ring and engaging said flange establishing a hinge connection between the closure and container and subjecting the closure to a sealing pressure upon a predetermined rotation of the closure.

2. The combination with a container having an opening, of a ring projecting from said container around said opening, a closure for said opening flanged to enclose said ring, and means establishing a hinge connection between the flange of said closure and said ring, the said hinge connection being detachable upon rotation of the closure.

3. The combination with a container having an opening, of a ring projecting from said container around said opening, a closure for said opening, said closure having a spiral shoulder thereon, and a member carried by

said ring and attaching the closure to said container, said member adapting the closure to swing between its open and closed positions in one position of rotation of the closure, and co-acting with said shoulder of the closure upon rotation from the specified position to press the closure into sealing engagement with the container.

4. The combination with a container having an opening, of a ring projecting from the container around said opening, a closure for said opening having a flange adapted to enclose said ring in the closed position of said closure, the flange of the closure being formed oppositely with spiral shoulders, and members projecting oppositely from said ring co-acting with said shoulders upon rotation of the closure in its closed position to subject the closure to a sealing pressure, one of said projections further forming a hinge mounting for the closure in one rotative position of the closure.

5. The combination with the filler tube of a radiator, of an adapter ring fitting within the mouth portion of said tube, means securing said adapter ring within said tube, a detachable hinge connection between said adapter ring and closure and means operable upon rotation of the closure to subject the same to a sealing pressure.

6. The combination with the filler tube of a radiator, of an adapter ring secured to said tube, a flanged closure for said tube adapted in its closed position for a limited rotation with respect to said tube, and means hinging the flange of said closure to said ring in one position of rotation of the closure, and subjecting the closure to a sealing pressure in another of its rotative positions, said means being normally fully concealed by the said closure.

7. The combination with a container having an opening, of a ring projecting from said container surrounding said opening having a spiral shoulder thereon, a closure for said opening and projections carried by said ring and engageable with the shoulder aforesaid to subject the closure to a sealing pressure upon rotation of the same.

8. The combination with a container having an opening, of a ring projecting from said container surrounding said opening, a closure adapted for a limited rotation around said opening, and a member carried by the ring and engaging the closure exercising a hinge function in one rotative position of the closure and subjecting the closure to a sealing pressure in another rotative position of the closure, said member and the connection thereof to the closure being fully concealed in the closed position of the closure.

9. The combination with a container having an opening, of a ring projecting from said container around said opening, a flanged closure for said opening, and means establishing

a hinge function between the flange of said closure and said ring fully concealed in the closed position of the closure, and means operable upon a rotation of the closure to effect a sealing pressure between the closure and the ring.

In testimony whereof I affix my signature.
CECIL R. CRARY.
